UNITED STATES PATENT OFFICE.

MORSE B. SCHAFER, OF ST. LOUIS, MISSOURI, ASSIGNOR TO THE AMERICAN STEEL BODY DOUBLE BOLSTER COMPANY, OF SAME PLACE.

CAR BODY-BOLSTER.

SPECIFICATION forming part of Letters Patent No. 640,827, dated January 2, 1900.

Application filed October 30, 1899. Serial No. 735,277. (No model.)

To all whom it may concern:

Be it known that I, MORSE B. SCHAFER, a citizen of the United States, residing at St. Louis, in the State of Missouri, have invented 55 a new and useful Improvement in Car Body-Bolsters, of which the following is a specification.

This invention relates to an integral body-bolster for railroad-cars, and is an improvement 10 on the body-bolster for which I obtained Letters Patent in the United States, dated June 6, 1899, No. 626,443, for an improvement in car-transoms.

This invention has for its object to increase 15 the rigidity of the body-bolster and to insure a positive and uniform distribution of the strain of the draft-gear thereto.

The invention consists in features of novelty, as hereinafter described and claimed, 20 reference being had to the accompanying drawings, forming part of this specification, whereon—

Figure 1 represents a transverse section through the sills of a railroad-car with my 25 improved body-bolster, shown in side elevation, applied thereto; Fig. 2, a top plan of the body-bolster; Fig. 3, a longitudinal vertical section through the body-bolster and transverse section through the car-sills on line 3 3 30 in Fig. 2; Fig. 4, a transverse section through the body-bolster longitudinally to the car on line 4 4 in Figs. 1 and 2; Fig. 5, an end elevation of the body-bolster as seen from the side of the car, and Fig. 6 a transverse section 35 through the body-bolster longitudinally to the car on line 6 6 in Figs. 1 and 2.

Like letters and numerals of reference denote like parts in all the figures.

My improved body-bolster A is composed 40 of two horizontal side plates a, which are arranged transversely to the car at a suitable distance apart and bear against the under sides of the inner car-sills 1 2 3. The side plates a are united at their ends by plates b, 45 which are at right angles to the side plates a and in the same horizontal plane therewith and bear against the under sides of the side sills 4, the plates a and b forming a rectangular-shaped frame which practically corresponds to the top plate or arch-bar of an ordinary car body-bolster.

Midway between the side plates a and parallel thereto, respectively, is a beam or girder c, arranged transversely to the car and united at its ends to the end plates b. The girder c 55 at its middle portion bears at the top against the under sides of the inner sills 1 and is preferably I-shaped thereat in cross-section, having the top and bottom flanges 5, vertical central web 6, and terminal walls 7, which 60 unite with the top and bottom flanges 5 and web 6 and preferably extend therefrom across the spaces between the girder c and the side top plates a and beneath the latter, to which they are united and serve as braces thereto. 65

Through the center of the middle portion of the girder c is formed the vertical hole d for the king-bolt, (not shown) and beneath the bottom flanges 5, around the hole d, is formed the center plate e for engaging the truck-bolster 70 in the usual well-known manner.

From the end walls 7, respectively, of the middle portion of the girder c extend, preferably, two parallel vertical webs 8, the upper edges or surfaces whereof are horizontal 75 and preferably in the same plane as the corresponding surfaces of the top flanges 5 of the middle portion of the girder c and the side and end top plates a b and bear against the under sides of the car-sills 2 3, the bottom 80 edges or surfaces of the webs 8 inclining upward or diminishing in depth from near the end walls 7 to the junction of the webs 8 with the end top plates b; or in lieu of two webs 8, as shown, one web only or more than two 85 webs may be used. The webs 8 are united to the adjacent side top plates a, respectively, by vertical braces or strengthening-ribs 9, disposed along the body-bolster A beneath the car-sills 2 and 4 or otherwise, as desired. Im- 90 mediately beneath the car-sills 3 the webs 8 are united at the top by cross-bars 10, which correspond in width to and bear against the under sides of the car-sills 3, respectively. From the cross-bars 10 the webs 8 incline up- 95 ward at the top toward the side sills 4, where they project above the end top plates b and are united thereat to each other and to the plates b by vertical cross-bars 11, forming lugs, which butt against the inner sides of the 100 side sills 4 and serve to strengthen the parts and check the end thrust of the body-bolster.

At a suitable distance from each end top plate *b* the webs *8* are united at the bottom by a cross-bar *12*, which projects beyond the outsides of the webs *8* and is braced to the latter 5 by inner and outer strengthening-ribs *13*. The cross-bars *12* are equidistant from the central hole *d* and constitute the side bearings of the body-bolster *A*.

Between the end walls *7* of the middle portion of the girder *c* and the central hole *d* for the king-bolt are two parallel webs or walls *14*, which intersect the vertical web *6* at right angles thereto and unite with the top and bottom flanges *5*. The webs or walls *14*, which 10 are opposite to each other at an equal distance, respectively, from the central hole *d*, extend from one side of the vertical web *6* across the space between the girder *c* and the corresponding side top plate *a* and beneath 15 the latter to a suitable distance beyond its outer edge, where they are united, preferably at the bottom, by a floor *15* and at the rear by a vertical web or partition *16*, which is united at the top to the said plate *a*; or in lieu of the 20 floor *15* these extended portions of the walls *14* may be closed at the top only, or they may be left open at the top and bottom, as desired. On the inside faces, respectively, of these 25 extended portions of the walls *14* are formed two vertical lugs *17*, the whole forming a 30 pocket *x* for receiving and guiding the strap draw-bar *f*, with its followers *g*, springs *h*, and draw-bar bolt *i*, of the ordinary-coupler draw-bar, as indicated by broken lines, in a 35 similar manner to the separate castings, with their lugs and guides, now used for that purpose and which have hitherto been bolted to the ordinary draw-timbers. The walls of the 40 pocket *x* are preferably braced at the top by horizontal flanges *14'*, which unite the said 45 walls externally to the outer edge of the top plate *a* adjacent thereto, the upper and under sides of the flanges *14'* being flush with the corresponding sides of the said plate. The 50 walls *14* extend from the other side of the vertical web *6* across the space between the girder *c* and the corresponding side top plate *a* and terminate beneath the latter, as in the case of the end walls *7* of the middle portion of the 55 girder *c*. These extended portions of the walls *14* are united beneath the said plate *a* by a vertical web *18*, which may be connected to the corresponding web of the body-bolster at the other end of the car by the bolt *19*, as indicated by broken lines.

In case it is desired to use the ordinary draw-bar spring-pocket attached to the draw-timbers in the usual manner in lieu of the draw-bar spring-pocket *x*, as above described, 60 the draw-timbers *k* may be inserted within the recesses *y*, formed, respectively, in the body-bolster *A* between the extended portions of the walls *14*, inclosing the pocket *x* and the corresponding parts of the end walls *7* of the 65 middle portion of the girder *c*, as indicated by broken lines, in which case the rear ends

of the draw-timbers *k* will butt against the vertical web *6* of the girder *c*.

Through the side top plates *a* and end top plates *b* and through the top flanges *5* and 70 bearing-bars *10* of the girder *c* are formed holes *20*, which are suitably disposed for receiving the bolts (not shown) by which the body-bolster *A* is secured to the car-sills. Similar bolt-holes *21* are formed through the 75 strengthening-flanges *14'* of the pockets *x* for receiving the bolts (not shown) by which the flanges *14'* are secured to the corresponding car-sills *1* and by which, in conjunction with the bolts through the corresponding 80 holes *20* of the top flange *5* and top plate *a*, the draw-timbers *k* are secured to the sills *1* when the draw-timbers *k* are used in lieu of the pocket *x*, as before mentioned. Holes *22* 85 are also formed through the walls *14* and *16* through the opposite extended portions of the end walls *7*, respectively, for receiving the bolts by which the draw-timbers *k*, when used, are secured within the recesses *y*.

The body-bolster *A*, with the combined 90 draw-bar spring-pocket and all the various parts formed and arranged substantially as hereinbefore described, is made integral throughout and preferably of cast-steel, the whole forming a rigid and durable structure. 95

If desired, the parts composing the draw-bar spring-pocket *x*—to wit, the extended portions of the walls *14*, with its floor *15*, connecting web *16*, lugs *17*, and strengthening-flanges *14'*—may be dispensed with and the body-bolster used alone in the usual manner.

I do not limit myself to the specific configuration and disposition of the parts composing the girder *c* as shown on the drawings, as these may obviously be modified without departure from my invention.

By this invention the strain of the draft-gear is distributed through the entire body-bolster and thence through all the car-sills uniformly, thereby steadyng the car and preventing undue and irregular strains thereon. Also by dispensing with the separate parts of the ordinary draw-bar spring-pocket and their attachments to the draw-timbers and combining these parts in a single piece the 115 construction of the pocket is simplified and rendered rigid and durable.

What I claim as my invention, and desire to secure by Letters Patent, is—

1. A car body-bolster composed of side and 120 end top plates united to each other and arranged together in the same horizontal plane, a beam or girder intermediate and parallel to the side top plates and united at its ends to the end top plates, the said girder consisting 125 of two parallel vertical webs united to each other and alined at the top to the top of the said plates and having their under sides below the plane of the said plates, and the said girder having a central hole, and having the 130 side bearings on its under side, and ribs uniting the said vertical webs respectively to the

corresponding side top plate, all the said parts being integral throughout, substantially as described.

2. A car body-bolster composed of side and end top plates united to each other and arranged together in the same horizontal plane, a beam or girder intermediate and parallel to the side top plates and united at its ends to the end top plates, and having its under side below the plane of the said plates, the said girder having a central hole and having the center plate and the side bearings on its under side and ribs uniting the girder to the side top plates, two opposite and parallel vertical webs or walls projecting from one side of the girder and extending beyond the corresponding side top plate, the extended portions of the said webs or walls having opposite vertical lugs and forming therewith a draw-bar spring-pocket, all the said parts being integral throughout, substantially as described.

3. A car body-bolster composed of side and end top plates united to each other and arranged together in the same horizontal plane, a beam or girder intermediate and parallel to the side top plates and united at its ends to the end top plates and having its under side below the plane of the said plates, the said girder having a central hole and having the center plate and the side bearings on its under side and ribs uniting the girder to the side top plates, two opposite and parallel vertical webs or walls projecting from one side of the girder and extending beyond the corresponding side top plate, these extended portions of the said webs or walls having opposite vertical lugs and forming therewith a draw-bar spring-pocket, and the said webs or

walls having external top flanges united to 40 the said side top plate the top and under sides of the said flanges being alined to the corresponding sides of the said plate, all the said parts being integral throughout, substantially as described.

4. A car body-bolster composed of side and end top plates united to each other and arranged together in the same horizontal plane, a beam or girder intermediate and parallel to the side top plates and united at its ends 50 to the end top plates and having its under side below the plane of the said plates, the said girder having a central hole and having the center plate and the side bearings on its under side, and ribs uniting the girder 55 to the side top plates, two opposite and parallel vertical webs or walls projecting from one side of the girder and extending beyond the corresponding side top plate, the extended portions of the said webs or walls having opposite vertical lugs, and the said webs or walls projecting from the other side of the girder having a vertical connecting-web, all the said parts being integral throughout, substantially as described.

5. A car body-bolster having a central hole and having the center plate and the side bearings on its under side, and having two opposite and parallel vertical webs or walls projecting from one side thereof, the said 70 webs or walls having opposite vertical lugs, and forming therewith a draw-bar spring-pocket, all the said parts being integral throughout substantially as described.
